APPARATUS FOR CONDITIONING AIR

Deane L. Nixon, Kansas City, Mo., assignor of
one-half to Stanley M. Hall, Kansas City, Mo.

Application October 24, 1932, Serial No. 639,201

4 Claims. (Cl. 62—131)

My invention relates to a method of and apparatus for conditioning air, and more particularly to the cooling and dehumidifying of air in residences, offices, or other places where conditioning of air is desired.

According to ordinary practice, air, to be cooled for lowering the temperature of a room or other area, is usually passed over or through a cooling medium such as a block of ice or a shower 10 of water with the result that in one instance temperature of the room is first lowered rapidly and the cooling effect diminished as the ice melts, with corresponding variation in dehumidification of the air, and in the other instance contact of 15 the air stream with the water shower involves variables requiring complicated apparatus for production of change in temperature of the air being conditioned.

It is the object of my invention to provide a 20 method and apparatus for conditioning air in areas like those above mentioned, in which the stream of air is not brought into direct contact with the cooling medium, thereby providing for a regulated and more uniform absorption of heat 25 and humidity from the air being conditioned and avoiding necessity for complicated and expensive apparatus.

In accomplishing this object of the invention I effect the method steps with apparatus, the 30 preferred form of which is illustrated in the accompanying drawing, wherein:

Fig. 1 is a perspective view of the apparatus illustrating air flow in response to operation of 35 an ordinary electric fan, here shown merely as illustrative of means for producing the air stream.

Fig. 2 is an enlarged central vertical section of the apparatus, particularly illustrating flow of 40 the air stream over the sides and beneath the cooling medium container.

Fig. 3 is a horizontal section on the line 3—3, Fig. 2.

Fig. 4 is a detail view of the upper portion of 45 the cooling medium container.

Referring more in detail to the drawing: 50 I designates the cooling medium container, here shown to consist of a metal can, square in cross section and of a size to contain an ordinary cake of artificial ice. The side walls 2 preferably meet at right angles forming the corners 3, 4, 5, and 6.

The can 1 has a closed bottom 7 and an open 55 top, the latter provided with outstanding right-angled flanges 8 for supporting a cover 9 having flanges 10 adapted to snugly fit within the upper portion of the can to substantially seal the interior thereof and form a seat for the periphery

of the cover member on the can flanges 8. The cover 9 is preferably stiffened by an inverted pan-like member 11 that may be welded or otherwise permanently secured to the cover member at the center thereof. A false bottom 12, preferably 5 formed as an inverted pan-like body having a perforated bottom 13 and side flanges 14, forms a chamber in the bottom of the can into which a melting ice cake 15, supported on the false bottom, may drain.

16 and 17 designate legs mounted on diagonal corners of the can 1 to support the can in tilted position when the ice cake 15 is positioned in the lower corner of the can. 18 designates a weight of angle construction adapted to fit over 15 the forward upper corner of the ice cake to retain the latter in place and in contact with the side walls of the can as the cake of ice melts, and thereby prevent floating of the cake on the water accumulating in the bottom of the can in response to the melting process. 20

I prefer to mount the can in a pan 19 having side walls 20 for assisting in direction of an air stream in contact with the lower portions of the sides and with the bottom of the can. The air 25 stream may be directed downwardly over the sides of and beneath the can by an electric fan 21 or other blowing agency.

In practicing my invention the can, charged with a cake of ice or other cooling medium, is 30 properly positioned in the area to be air conditioned and the fan or other blower arranged to direct a stream of air downwardly over the lower portions of the side walls of the can and beneath the can so that the air stream contacts 35 such wall portions and is cooled during its flow thereover, it being apparent that by thus directing the air currents the air, flowing along the can, will contact the coolest portions thereof, since the colder water by thermo syphon action 40 will move toward the lowermost part of the container while the warmer water rises to the surface.

When the cooling medium consists of a cake 45 of ice, the ice melting forms a body of cool liquid in the lower portion of the can for continuing the cooling influence on the air current as the ice melts and even after the ice cake has been entirely transformed into cool water. By confining the cake of ice or other cooling medium, the 50 air currents are kept from direct contact therewith so that the air is not humidified as in use of the ordinary cooling apparatus but, on the contrary, is dehumidified by the giving up of its moisture content through condensation on the 55

container and this action, as well as the cooling effect, is continued at relatively uniform efficiency during the entire operation. Also the speed of such action relative to a given quantity of cooling medium used can be regulated to the needs of the area to be conditioned by the use of metal or other substance of varying degrees of conductivity.

If ice is used for the cooling medium the vessel 10 may be filled by freezing the water therein or the container may be inverted and slipped over a block of ice of a size to substantially fill the vessel, whereupon the container is turned to upright position and placed in the stream of air.

15 It will be evident that a plurality of containers could be positioned in a single air stream and mounted in a single pan if desired.

It will be further evident that if desired the can may be tilted by resting it on two sides and 20 the bottom of the pan or by supporting means other than the legs shown.

What I claim and desire to secure by Letters Patent is:

25 1. Apparatus of the character described including a container for a cooling medium and having diagonal corners, and legs on said diagonal corners of the container for supporting the container in inclined position.

2. Apparatus of the character described includ-

ing a container for a cooling medium having side walls and diagonal corners, legs on said diagonal corners of the container for supporting the container in inclined position, and means in the container for retaining a block of cooling medium 5 in contact with the lowermost of said side walls of the container.

3. Apparatus of the character described including a container having diagonal corners, a false perforated bottom forming a liquid collection chamber at the bottom of the container, and 10 legs on said diagonal corners of the container for supporting the container on an intermediate corner and said legs.

4. In an air conditioning apparatus of the character described, a container for a frozen cooling medium normally fluid at ordinary temperatures and including a pair of adjoining angularly divergent side walls having inner and outer contact surfaces, means for supporting the container 20 with adjoining edges of the side walls positioned at an angle whereby the inner surfaces of said side walls form a direct contacting support for the cooling medium so that fluid melting therefrom flows directly against and over said inner surfaces of the side walls, and means for circulating air to be conditioned in direct wiping contact 25 with the outer surfaces of said walls.

DEANE L. NIXON.
